MERCURY VAPOR DISCHARGE DEVICE

Wilber L. Meier, Arlington, N. J., assignor to
 Radio Corporation of America, a corporation
 of Delaware

Application September 22, 1933, Serial No. 690,514

6 Claims. (Cl. 250—27.5)

My invention relates to electron discharge devices, and more particularly to grid actuated hot cathode vapor tubes or vapor converters.

One commonly used vapor tube of this type has a highly evacuated bulb containing a small amount of mercury and enclosing a hot cathode, an anode, and an interposed grid electrode. In such a tube the grid can start the current flow, but cannot control or stop it, and regains control only if the current stops, as it will do when the voltage on the anode becomes zero or negative. For a given anode voltage there is a definite and critical grid voltage at which the current flow starts, and the commercial tubes are usually so designed that this critical or breakdown grid voltage is a few volts positive.

Tubes of this kind as usually constructed for commercial purposes operate most satisfactorily and with the highest efficiency at temperatures of around 60° C. The most desirable operating temperature is within the temperature range of from 55° C. to 70° C. where these tubes have the peculiar characteristic of a double breakdown grid voltage, and may break down at either the designed breakdown positive grid voltage of several volts positive, or at a slightly negative grid voltage. The shift between these very different grid breakdown voltages is erratic and uncontrollable, is governed by various obscure factors, and is a serious disadvantage in some commercial applications of the tubes.

Tubes of the type described are used generally for various purposes and in various circuits. In one desirable application to self-starting converters for changing direct current to alternating current, the commercial tubes constructed in the usual way and having the double breakdown grid voltage characteristic frequently break down to pass current before the cathode has reached its full emission, so that not only is proper operation of the circuit interfered with, but the cathode of the tube may be destroyed. Another disadvantage of this type of tube as usually made is that the grid current at starting is comparatively high and increases with the life of the tube. This property makes difficult the design of an efficient circuit which will operate with the tube, and the increase during the life of the tube in the current taken by the grid at starting requires continual adjustment of the circuit constants in order to have the circuit operate properly.

An object of my invention is to provide a grid controlled electron discharge device of the type described in which the grid starting voltage is

substantially constant for any operating temperature.

Another object of my invention is to provide an electron discharge device of the character described which has definite positive grid starting voltages over a wide range of anode voltages. 5

Still another object of my invention is to provide a device of the character described in which the current taken by the grid at starting is small to permit efficient and easily designed associated 10 circuits and in which the grid current at starting remains substantially constant during the life of the device.

To these ends and in accordance with my invention the single control grid heretofore used is replaced by two equi-potential perforated grid-like metal sheets or inserts mounted in parallel planes with the perforations in the grid-like inserts and the spacing between the inserts having definite and fixed relationships. 15

The novel features which I believe to be characteristic of my invention are set forth with particularity in the appended claims, but the invention itself will best be understood by reference to the following description taken in connection 20 with the accompanying drawing in which:

Figure 1 is a perspective longitudinal section of an electron discharge device embodying my invention;

Figure 2 shows a schematic diagram of one 30 circuit arrangement using electron discharge devices of the type shown in Figure 1.

Figure 3 is a chart showing the relationship of the grid starting volts and the condensed mercury temperatures for a single grid electron discharge device of the type described and for an 35 electron discharge device embodying my invention;

Figure 4 is a diagram showing the relative 40 shielding effect of the control grid with respect to the distance between the grid inserts in an electron discharge device embodying my invention.

Referring to the drawing the evacuated dome type envelope 10 has the usual stem and press 45 11, and the usual base 12. The envelope contains a small amount of mercury 13 to provide the mercury vapor which gives the tube its peculiar grid control characteristic. Supported within the envelope from the top is the disk-shaped anode 14 electrically connected to the cap 15 on the outside of the envelope. The cathode 16 is preferably of the well known multi-cellular oxide coated type, heat shielded except for the open end from which the electrons 50 55

emerge, and has a heater 17 supplied with current in the usual manner by conductors 18 extending through the press 11. The cathode assembly is supported on the press 11 by side rods 19.

The grid or control electrode comprises two perforated sheet metal discs or grid inserts 20 and 21 electrically connected and mechanically supported in spaced parallel planes perpendicularly to the longitudinal axis of the tube by the perforated heat radiating metal collar or sleeve 22, which at one end overlaps the cathode 16 and at the other end overlaps the anode 14. To provide a tube having a single breakdown voltage the spacing between the grid inserts 20 and 21 should be approximately equal to the diameter of the perforations in the grid inserts. For practical reasons this spacing is usually made slightly greater than the diameter of the perforations when the tube is assembled. The perforations in the grid inserts are in actual or effective alignment which permits current flow from the cathode to the anode.

It has been found that for 110 volt operation a device of the character described operates most satisfactorily if the grid inserts are spaced about 100 mils. apart and each has about nine uniformly spaced circular perforations per square inch, each perforation being about 90 mils. in diameter. The anode is about five millimeters from the top insert and the top of the cathode is about eleven millimeters from the bottom insert. As the perforations are made smaller the grid voltage necessary to cause breakdown of the tube increases sharply, which is undesirable as the correspondingly increased grid current reduces the efficiency of the associated circuits and makes their design very difficult. As the perforations are made larger the tube loses its positive grid breakdown characteristic and breaks down at negative grid voltages which is not desirable for commercial uses.

This double grid arrangement acts to shield the anode more effectively than the usual single grid and eliminates the double breakdown voltage characteristic of the single grid tube. The grid electrode structure is supported by grid side rods 23 secured to a collar 24 which is clamped on the stem 11. The upper end of the cathode is tied to the grid by the glass bead spacers 25 between the cathode and the side rods 23.

In Figure 2 is shown one application of electron discharge devices embodying my invention as used in a self-starting converter circuit. The transformer 26 has a primary 27 and a secondary 28 to which the load 29 is connected, the primary 27 of the transformer being connected to a D. C. supply line through a pair of electron discharge devices 10 and 10' each constructed as shown in Figure 1.

The anodes 14 of tubes 10 and 10' are connected to opposite ends of the primary 27 of the load transformer, and are also connected to each other through a commutating condenser 30 which is in shunt with the primary 27 of transformer 26. The cathodes 16 of the two tubes are connected by cathode leads 31 to the negative side of the D. C. supply lines to which the heaters 17 of the two tubes are connected. The midpoint of the primary 27 of the transformer 26 is connected to the positive side of the D. C. supply line through a switch 32 and an inductance 33 which prevents alternating voltages being impressed on the direct current supply lines.

75 The device is started by closing the switch

32, thereby energizing the cathodes 16 and impressing an operating voltage on the anodes 14 of the two tubes through the inductance 33 and primary 27 of transformer 26. If the grid 22 of the tube 10 is at a sufficiently high positive voltage, when the cathode 16 attains full emission, the tube will break down, whereupon a self-sustaining discharge will flow between the cathode and anode and complete a circuit from the positive side of the D. C. supply line through the inductance 33, the left half of the primary 27 of transformer 26 and the cathode lead 31 to the negative side of the D. C. supply line. The resulting rush of current through the primary 27 will induce a voltage in the secondary 28 and also build up a voltage difference between the ends of the primary winding 27 which is in effect an autotransformer which impresses on the condenser 30 a charge of about twice the supply voltage, minus the drop through the inductance 33 and the drop through the tube 10 with the right hand plate of the condenser 30 positive and at the higher potential.

If now a breakdown voltage is applied to the grid of the tube 10' the breakdown of the tube 10' and resultant flow of current through it will in effect connect the right hand highly positive plate of the condenser 30 to the negative side of the supply line through the cathode lead 31 of the tube 10'. The voltage on the right hand plate 30 of the condenser drops from the positive value to which it was charged down to a voltage substantially equal to the small drop through the self-sustaining discharge in the tube. The left hand plate of the condenser 30 suffers instantaneously an equal drop on account of the high transient impedance of the transformer winding compared to that of the condenser, and since it was already at a very low positive potential this left hand plate of the condenser goes negative, 40 and causes the anode 14 of the tube 10 to which it is connected to go negative momentarily, thus stopping the discharge through the tube 10. The self-sustaining discharge in the tube 10' permits current to flow through the right half of the primary 27 and the condenser 30 will be reversely charged with the high positive potential on the left hand plate. Tube 10 again becomes conductive when a breakdown voltage is applied to its grid, whereupon the anode of tube 10' goes negative and the self-sustaining discharge in that tube stops. Alternately impressing breakdown voltages on the grids thus causes the current to flow alternately and in opposite directions through the primary 27 of transformer 26 thus inducing an 55 alternating voltage in the secondary 28.

In order to impress a breakdown voltage on the grids of the two tubes alternately, use may be made of the grid voltage control circuit shown in Figure 2, and comprising condenser 31', and a 60 resistor 32, connected in series with the primary 33 of a transformer 34 which is in shunt with one-half of the primary 27 of transformer 26 and has a secondary 35 with its opposite ends connected to the grids 22 of the two tubes through resistors 36. Normally, a sufficient positive voltage to cause breakdown of the tube is impressed on the grids 22 of both tubes by a potentiometer 37 connected across the supply lines.

In a tube embodying my invention as the mercury temperature increases, the grid voltage necessary to produce breakdown decreases slightly up to some predetermined temperature and then has a substantially constant value. The potentiometer is, therefore, so adjusted that the 75

voltage applied to the grid to cause the tube to break down is as small as possible and is such that for any particular operating conditions, on starting up the inverter, the cathode will reach 5 full operating temperature and emission before the mercury reaches a temperature at which the applied grid voltage will cause breakdown of the tube. Thus no time delay devices are necessary to apply the anode voltage after the cathodes 10 have heated up.

After the switch 32 is closed, due to slightly different characteristics inherent in tubes of the character described one of the tubes will break down before the other and pass current. Assuming that tube 10 breaks down and passes current, 15 current will flow through the left half of the primary 27 of transformer 26 as explained above.

Since the grid voltage applying circuit is connected across one-half of the primary 27 the 20 voltage which is induced in this half of the primary as the current therethrough builds up to a maximum, is applied to the grid voltage applying circuit. This induces a voltage in the secondary 35 of the transformer 34 such that a negative voltage is applied to the control electrode 22 of 25 tube 10' thereby preventing breakdown of this tube at this instant. As the current through the tube 10 approaches a maximum the induced voltage in the primary 27 decreases. Since this is the 30 voltage relied upon to energize the primary 33 of the transformer 34, the induced voltage in the secondary 35 also drops thus permitting the electrode 22 of tube 10' to become positive and break down to pass current. When the tube 10' passes 35 current the left side of condenser 34 drops to a negative value as explained above to momentarily cause the anode 14 to become negative, thus interrupting the flow of current through the tube 10. Since the induced voltage in primary 27 of 40 transformer 26 is now reversed, the voltage applied to the primary 33 of the grid transformer 34 is also reversed applying a negative bias to control electrode 22 of tube 10 which will prevent this tube from breaking down at this instant. 45 When the induced voltage in secondary 27 drops, electrode 22 of tube 10 again goes positive and causes tube 10 to break down repeating the operation described above. The current flowing alternately through opposite halves of the primary 27 of the transformer 26 in this manner, induces an alternating voltage in the secondary 28. The circuit comprising the condenser 31, resistor 32 and transformer 34 is so designed as to give the proper time and phase relation between the anode and grid voltages to bring about 50 the operation described.

In Figure 3 the curves "a" and "b" show the grid breakdown voltages for different mercury temperatures for a single grid electron discharge 55 device of the type described. These curves are only approximate and vary with different tubes and with the age of the tube, the curves "a" and "b" approaching each other as the tube ages and in some instances overlapping. Curve "c" shows the definite and substantially constant grid breakdown voltage for an electron discharge device embodying my invention. In a single control grid tube in the region outlined by curve "a" very little or no grid breakdown voltage is necessary 60 to cause the tube to break down. Hence with a single grid tube in the inverter circuit and at the normal operating temperature of around 60° C., the potentiometer which is depended upon to apply the breakdown grid voltage would be rendered useless to prevent breakdown of the tube 65

until the cathode had reached full operating temperature and emission. This, of course, means that if the temperature of the mercury is within the double breakdown region that as soon as the cathode starts to heat up the tube will break 5 down, the current through the tube slowly building up to a maximum as the cathode approaches full emission. The current building up slowly through the tube and associated circuit would, therefore, fail to induce the voltages upon which 10 proper operation of the grid voltage applying circuit depends. A transfer of current from one tube to the other would not take place and the tube which first broke down and passed current would cause a short circuit through that tube 15 with the resulting instantaneous destruction of its cathode. In tubes having a single grid breakdown voltage characteristic such as the tubes embodying my invention the potentiometer can be properly adjusted so that the tubes will not break 20 down until the cathode of the tube has reached its full emission state as pointed out above. Thus a tube embodying my invention provides the automatic time delay characteristic which makes 25 a self-starting inverter circuit feasible. 25

In tubes having a positive grid breakdown voltage, a certain amount of grid current must flow before the tube will break down. A tube embodying my invention requires a smaller grid starting current than the conventional single grid 30 tube and this current remains substantially constant during the life of the tube which was not true of the single grid tubes. The smaller grid current results in greater efficiency of the circuits used with the tubes since the power taken 35 by the grid circuit is decreased. The constant grid current during the life of the tube makes it possible to determine the constants for a particular circuit without requiring change during the life of the tube. This also makes it possible to 40 substitute tubes embodying my invention for each other in a circuit without making any necessary adjustments for the newly substituted tube.

The relative shielding effect of the double grid electron discharge device as the distance between 45 the grid inserts is increased is shown graphically in Figure 4. The distance "d" is equivalent to the diameter of the perforations in the grid inserts. This curve indicates that as the distance between the grid inserts is increased the shielding 50 of the anode becomes more effective and the double breakdown grid voltage becomes less likely, this double voltage characteristic being practically eliminated when the distance between the grids is equal to the diameter of the perforations in the grids. 55

While I have indicated the preferred embodiments of my invention of which I am now aware and have also indicated only one specific application for which my invention may be employed, it 60 will be apparent that my invention is by no means limited to the exact forms illustrated or the use indicated, but that many variations may be made in the particular structure used and the purpose for which it is employed without departing from 65 the scope of my invention as set forth in the appended claims.

What I claim as new is:

1. An electron discharge device including an envelope containing an ionizable medium for supporting a self-sustaining discharge through said device and enclosing a thermionic cathode, an anode, and an equipotential control electrode interposed in the path of discharge between said cathode and anode and comprising a pair of par-

allel metal sheets, each having a plurality of circular perforations of uniform diameter and mounted with the perforations in effective alignment, the spacing between said sheets being substantially equal to the diameter of said perforations.

2. An electron discharge device including an envelope enclosing a thermionic cathode and an anode, and containing an ionizable medium for supporting a self-sustaining discharge through said device, and a control electrode including a pair of discs electrically connected and each having a plurality of circular perforations, said discs being positioned in parallel planes with the perforations in effective alignment, and spaced substantially equal to the diameter of said perforations.

3. An electron discharge device including an envelope containing an ionizable medium for supporting a self-sustaining discharge through said device, and enclosing a thermionic cathode, an anode, and a control electrode interposed between said cathode and anode and including a tubular member with its longitudinal axis in alignment with said cathode and anode, and a pair of parallel transverse discs inside of and intermediate the ends of said tubular member, each of said discs having a plurality of circular perforations, and said discs being spaced apart a distance substantially equal to the diameter of said perforations and with the perforations in said discs in effective alignment.

4. An electron discharge device including an envelope containing an ionizable medium for supporting a self-sustaining discharge through said device and enclosing a thermionic cathode, an anode, and a control electrode including a tubu-

lar member in registry with said cathode and said anode, and a pair of parallel transverse perforated discs intermediate the ends of said tubular member and spaced from each other substantially the diameter of the perforations in said discs and with the perforations in said discs in effective registry, said anode and said cathode being mounted at opposite ends of said tubular member.

5. An electron discharge device comprising a highly evacuated envelope containing mercury and enclosing a thermionic cathode, an anode, and a unipotential control electrode comprising a tubular member having a pair of parallel perforated metal sheets mounted with their perforations in registry to extend transversely of the discharge path between said cathode and anode, the spacing between said sheets being substantially equal to the diameter of the perforations in said sheets.

6. An electron discharge device comprising a highly evacuated envelope containing mercury and enclosing a cylindrical oxide coated thermionic cathode, a flat circular anode in registry with the end of said cathode, and a unipotential control electrode comprising a perforated metal sleeve mounted to surround the discharge path between said cathode and said anode with one end overlapping said anode and the other end overlapping the end of said cathode, and a pair of parallel perforated metal discs set inside and transversely of said sleeve with a spacing substantially the same as the diameter of the perforations in said discs and with the perforations in said discs in registry.

WILBER L. MEIER.
